UNITED STATES PATENT OFFICE.

ROBERT C. EDWARDS, OF ELIZABETH, NEW JERSEY, ASSIGNOR TO RADIO CORPORATION OF AMERICA, A CORPORATION OF DELAWARE.

DESIGN FOR A CABINET FOR RADIORECEIVERS.

Application filed July 19, 1924. Serial No. 10,193. Term of patent 14 years.

To all whom it may concern:

Be it known that I, ROBERT C. EDWARDS, a citizen of the United States, and resident of Elizabeth, New Jersey, have invented certain new, original, and ornamental Design for Cabinet for Radioreceivers, of which the following is a specification, reference being had to the accompanying drawing, forming part thereof.

The figure of the drawing is a perspective view of a cabinet showing my new design.

I claim:

The ornamental design for a cabinet for radioreceivers as shown.

ROBT. C. EDWARDS.
